ABSTRACT: A centrifugal iron pipe casting apparatus with twin ladles each with a pouring trough arranged for movement of one ladle and trough into pouring position while the other is moved out of pouring position for filling and cleaning. The ladles are mounted on a carriage provided with downwardly facing supporting rails running on fixed rollers to avoid any deposit on the rails which would interfere with smooth travel. A fluid pressure actuating device moves the carriage back and forth and terminal cushioning means ensures smooth acceleration and deceleration.

U.S. PATENT 3,522,837
CENTRIFUGAL PIPE CASTING

This invention relates to an apparatus and method for casting iron pipe.

The conventional method of casting iron pipe involves a cycle in which a mold carriage is moved back and forth between a position in which the pouring of the metal is started to a position where the pouring is finished. A trough extends within the mold leading from the ladle. As iron is poured from the ladle and flows from the trough into the mold, the mold carriage moves away from the ladle. The rotation of the mold and the movement of the carriage are synchronized in conjunction with the pouring of the iron. Once the pipe is completed, the ladle must be filled again and the trough cleaned before the carriage can be moved back to pour another pipe. This takes time and delays the return of the carriage so that the mold is not used to maximum capacity.

It is an aim of the present invention to remedy these shortcomings with the conventional apparatus and to provide certain positive advantages as will be clear from the following description.

The invention provides an apparatus for casting iron pipe in which there is a carriage mounting a plurality of ladles and a trough operatively related to each ladle. The carriage is adapted for movement between positions in which each of the respective ladles are in pouring position. Means is provided for moving the carriage between these positions and control means is provided for controlling the movement in such a manner.

The invention has been generally described and it will now be referred to in more detail by reference to the accompanying drawings, which illustrate preferred embodiments, and in which:

FIGURE 1 is a plan view showing a general arrangement of a casting machine according to the invention with the mold carriage in "down" position and the ladle carriage positioned so that one of the ladles is ready to pour and its trough ready to receive the mold.

FIGURE 2 is a similar view to **FIGURE 1**, but with the ladle carriage moved so that the other ladle and trough are in pouring position.

FIGURE 3 is a side elevation, partly in section, showing the apparatus of **FIGURES 1** and **2** with the mold carriage in "down" position, dotted lines showing its "up" position.

FIGURE 4 is a rear elevation of the apparatus on a greatly enlarged scale, showing particularly the arrangement of the ladles and operating mechanism on the ladle carriage.

FIGURE 5 is a side elevation, generally on the plane of line 5-5 of **FIGURE 4**, on the scale of **FIGURE 4**, showing the ladle carriage and ladles.

FIGURE 6 is a horizontal cross-section, partly in elevation, on a still further enlarged scale, showing the ladle carriage-operating cylinder and hydraulic connections.

Referring especially to **FIGURES 1** to **3** a general arrangement of the casting machine is shown. An inclined bed 15 extends from adjacent to the upper or pouring end to the lower or pipe discharge end (from left to right in **FIGURES 1** to **3**) and a mold carriage A is adapted to run on rails along this bed during the process of casting. A motor 25 is shown for rotating the mold as the carriage A advances from the upper end of the bed 15 toward the lower end, during pouring of the iron. A bell core 23 is supplied to the mold to form the end of the cast pipe, as well understood, during the casting operation. The nature of the mold and other features so far described are standard. 44 are skids which swing out of the way for movement of the carriage A along the bed 15 but which are brought into the position vacated by the carriage to receive the cast pipe and carry it off to one side.

In accordance with the invention, a carriage B is provided which travels transversely of the mold at the upper end of the bed 15. The carriage is moved by a hydraulic cylinder (not shown) within the bed 15. This carriage includes twin pouring troughs C and C1 and twin ladles D and D1, details of which will later be described.

The carriage B is supported by a pair of parallel spaced apart horizontally extending rails 31 and 33 having downwardly extending running surfaces which run on pairs of spaced apart smooth surfaced rollers 35 and flanged rollers 36 which are suitably journaled in brackets 39 and 41 respectively in a line perpendicular to the direction of travel of the carriage A. 42 represents a water cooling device.

The ladle D has axles 51 and 51a carried in respective journals 53 mounted on a superstructure 55 on the carriage B. An electric motor 57 has a drive connection with a speed reducer 59 which in turn has a driving connection through a crank arm 65 pivotally connected to a rod 67 which is in turn pivotally connected to a pin 69 on the side of the ladle D. The arrangement of the ladle D1 and its parts are similar and the same parts as those of ladle D have been identified by the same numerals qualified with "a".

The carriage B is arranged to be moved back and forth between a pouring position for the ladle D to a pouring position for the ladle D1. The mechanism by which this is accomplished is as follows.

The cylinder 70 is fixedly mounted on the underside of the frame of the carriage B by brackets 71. A piston 73 operates within the cylinder 70 and is connected to a piston rod 75 which is anchored at one end to a stationary block suitably anchored to the floor. The cylinder 70 is provided at its respective ends with extension chambers 76, 77 of reduced diameter. The piston 73 is provided at one side with an extension 78 and at the other with an extension 79, these extensions being adapted to enter respectively the extension chambers 76, 77 in a sliding fit as the piston nears the ends of its stroke.

A pipe carrying water pressure, say at 160 pounds per square inch, extends from a source of water supply to a valve 84. A pipe 82 extends from the valve 84 to a drain. Pipes 86 and 87 respectively extend from the valve 84 to a valve 85. Pipes 88 and 89 respectively connect the valve 85 to inlet-outlets 91 and 93 respectively spaced from the respective ends of the cylinder 70. The valves 84 and 85 can be manipulated to cause fluid to enter the cylinder through the lines 88 or 89, thus causing the piston 73 to move in one direction or the other. A by-pass passage 95 extends from the extension chamber 76 to the line 88 and a by-pass passage 96 extends between the end of the extension chamber 77 to the pipe 89.

In operation, when the piston 73 nears the end of its travel, say, going in the right-hand direction, it will close off the outlet 93 and the extension 78 will enter the extension chamber 76 and will be cushioned by the fluid in the extension chamber 76 and will thus slow down gradually. This is important to the operation of the apparatus since it is necessary to prevent any jerking movement or abrupt stop of the carriage B, so that molten iron will not be spilled from either of the ladles D or D1. The feature that the surface of the rails 31, 33 of the ladle carriage face downward also prevents the possible deposit of iron on the receiving surfaces which could occur if they were facing upwards, thus ensuring a smooth ride of the rails over the rollers 35 whose surfaces are protected by the rails.

As will be well understood by one skilled in the art, there is inherent in the operation of a centrifugal pipe casting machine of this general type, an automatic circuit which controls the movement of the carriage A longitudinally of the tracks, the rotation of the mold, and the extractor, etc.

Tied in with this are special control features according to the invention. For the purpose of explaining these control features, a casting cycle will be considered. A pipe is about to be poured and the carriage A has come to the "up" position. The core 23 is set by mechanism mounted on the carriage A, as for example, mechanism shown in United States Patent 3,168,765 Bernhardt, February 9, 1965. Once the core is set the rotation of the mold is brought up to speed and the ladle D, which is in pouring position tilts automatically. For safety's sake the pouring of the iron does not start automatically when the core goes into position for fear that it might not be properly in position, and, actually, the starting of the pour is by an operator pushing a button. The operator waits till the molten iron starts pouring over the lip of the ladle and, by judgment of the proper timing,

pushes another button to start the carriage A moving from the left to right, referring to FIGURE 3, from the "up" to the "down" position, and the pipe is progressively poured. When it reaches this point, the pipe spins while it cools to a certain degree. The bell core 23 then swings open, the extractor is inserted and the carriage is moved to the left again to the "up" or pouring position.

While the pipe is being cooled, the ladle carriage B is caused to move transversely so that the ladle D1 comes into pouring position. D1 has previously been filled with molten iron at a 10 convenient time between pours by an operator with a transfer ladle carried by an overhead crane from a cupola where the transfer ladle is filled. With ladle D1 in place, the extractor is pushed into the end of the pipe after the bell core 23 has been removed. The extractor grips the pipe and the mold carriage A 15 moves uphill again from right to left from "down" to "up" position and, at the same time, the pipe is extracted. Once the carriage A is in the "up" position, the cast pipe is transported away sideways to an annealing operation. Then, while the pipe is cooling, the operator sets another core 23 on the machine 20 and this core is placed in the end of the pipe in the mold carriage A, and the apparatus is ready to pour another pipe.

There are two limit switches in the automatic circuit which control the tilt of the respective ladles. If anything goes wrong in the automatic circuit, the ladle will remain in the non-pouring position.

A sliver of iron remains in the bottom of the trough C or C1 as the case may be, after the pouring of the pipe. This has to be removed between pours. As soon as the mold carriage gets clear of the trough which has just been used to pour a pipe, the operator starts working to remove the sliver. The present apparatus permits the sliver to be removed from the trough, which is not in service, just as soon as the previous pipe has been removed from the mold carriage and without holding up the pouring of another pipe. There is no delay in pouring the next pipe, because the two ladles and pouring troughs work independently.

I claim:

1. A centrifugal casting machine comprising, in combination,
a mold carriage;
tubular mold means rotatably supported on said carriage;
means on said carriage in operative engagement with said
mold means for rotating the mold means as it is charged
with a molten metal and for reciprocating the mold
means along a path of travel about which said mold
means rotates;
support means reciprocably restricting said carriage for
movement along said path of travel between an "up"
and "down" position on said path of travel; and
dual-pouring-ladle means at the "up" position of said sup-
port means whereby said mold means can be im-
mediately charged with molten metal during each cycle
between the "up" and "down" positions with a
minimum expenditure of time and with maximum effi-
ciency;
said dual pouring-ladle means comprising guide track
means extending transversely of the "up" position of
said mold means path of travel;
a ladle-support frame reciprocably supported on said
guide track means,
power means operatively connected to said ladle-support
frame for positioning the frame in one of two positions,
a pair of pouring ladles pivotally mounted on said ladle-
support frame on axes of oscillation parallel to said
guide track means,
said pair of pouring ladles being respectively disposed in
one of said two positions of said ladle-support frames.

said pouring ladles including elongated, mutually parallel
pouring troughs communicating at one end with said
pouring ladles and extending down the path of travel of
said mold carriage on said support means and respec-
tively positionable axially within said tubular mold
means in relation to one of the positions of said ladle-
support frame; and

power-tilting means on said ladle-support frame and
operatively connected to the respective pouring ladles
whereby one pouring ladle and spout can be cleaned
and the one ladle can be filled with molten metal while
the other pouring ladle can be used to progressively
pour molten metal into the tubular mold means as the
mold means is moved from the "up" to "down" posi-
tions while the mold means is rotated, and thereafter,
after a molded article has been removed, the mold
means can be moved axially onto the pouring spout of
the one pouring ladle which was subsequently filled
with molten metal and molding of another article can
be substantially immediately accomplished when the
mold means reaches the "up" position.

2. The combination as claimed in Claim 1, said support
frame comprises a pair of depending guide rails disposed in
mutually parallel relation and having downwardly-facing
running surfaces, guide rollers journaled on axis of rotation
normal to the path of movement of said ladle-support frame
and engaged by said depending guide rail running surfaces
whereby spilled molten metal is substantially eliminated from
said rollers and rail running surfaces.

3. The combination as claimed in Claim 2 in which the
guide rollers engaging one of said guide rails includes an annu-
lar groove for restrictively retaining the rail in its path of
reciprocation.

4. The combination as claimed in Claim 1 in which said
power means operatively connected to said ladle-support
frame comprises a piston-and-cylinder disposed parallel to the
guide track means for said ladle-support frame,
the piston being fixedly anchored at one end and includ-
ing an integral piston defining variable-volume fluid
chambers on opposite sides thereof,

40 said piston being fixedly secured to a lower portion of said
ladle-support frame,
and a fluid-pressure system operatively connected to op-
posite ends of said cylinder in spaced relation from the
ends thereof whereby movement of said piston to the
respective ends of said cylinder defines the two posi-
tions of said ladle-support frame.

5. The combination as claimed in Claim 4 in which said
piston comprises axially projecting, reduced-diameter por-
50 tions at opposite sides thereof, the cylinder including terminal,
reduced-diameter end portions substantially complementary
to the end portions of said piston, and supplemental fluid
pressure by-pass lines connected to the terminal ends of the
reduced-diameter end portions of said cylinder and said fluid
pressure system whereby the terminal travel of said piston
relative said cylinder is substantially damped as the frame
reaches either of said two positions of orientation.

6. The combination as claimed in Claim 1 in which said sup-
port frame includes pairs of vertically disposed, axially-aligned
journal portions, said pouring ladles including axially aligned
stub shafts respectively journaled in said journal portions; said
power-tilting means comprising two independent motor-and-
speed reducer assemblies on the frame, a crank arm projecting
from the motor-and-speed reducer assemblies, and a force
transmitting rod pivotally connected to said crank arm at one
end and pivotally connected to a respective powering ladle ec-
centrically of the axially aligned stub shafts.
